MATTRESS

Edward Rose, Newton, Mass., assignor to Rose-Derry Company, Newton, Mass., a corporation of Massachusetts

Application October 24, 1936, Serial No. 107,429

1 Claim. (Cl. 5—356)

This invention relates to mattresses and is more especially concerned with those designed for use in cribs and cots for small children.

The invention aims to improve the construction of mattresses with a view to providing effective protection for the internal structure of the mattress against wetting, while at the same time producing an article which can be manufactured economically, and which can be easily cleaned and thus kept in a thoroughly sanitary condition without the use of the waterproof mattress covers, pads, and the like, which have been commonly used heretofore to protect the mattress.

The nature of the invention will be readily understood from the following description when read in connection with the accompanying drawing, and the novel features will be particularly pointed out in the appended claim.

In the drawing,
20 Figure 1 is a perspective view of a mattress embodying the invention;

Fig. 2 is a vertical, sectional view, partly in elevation, of a portion of the mattress shown in Fig. 1; and

Fig. 3 is a sectional view on a large scale through one of the tufts and the adjacent portion of the mattress.

The mattress shown in the drawing may be of any common or usual construction so far as its general nature is concerned. That is, it may be of any suitable dimensions, may either have internal springs, or be filled solid with the usual mattress filling materials, such as hair, cotton felt, or the like. It differs, however, from the ordinary mattresses in having an envelope or tick 2 made of waterproof sheet material. Such material may consist, for example, of rubberized fabric, or of sheeting or similar goods coated with other waterproof compounds. A very satisfactory material for this purpose consists of fabric coated with a solution of some of the cellulose esters, such as cellulose acetate, in which a sufficient proportion of plasticizer is included to make the coating very flexible. Coating compounds of this nature are readily obtainable in the open market.

In order to hold the mattress in shape, it is tufted. In the particular construction shown the tufts consist of buttons 3, but any other suitable form of tuft can be used. It is desirable, however, that the tufts be waterproof so that they will not absorb and hold moisture in any substantial volume. These tufts are distributed at suitable intervals over the top and bottom surfaces of the mattress and are arranged in pairs

in the usual way, each top tuft being secured to a bottom one by a string, tape, cord, or the like, such a connecting means being hereinafter designated by the term "cord", and these elements being indicated in the drawing at 4.

Even though the envelope 2 is impervious to water, nevertheless if water does rest on the top of the mattress, it will work down into the body of the mattress through the holes necessarily provided for the passage of the cords 4 that secure the top and bottom tufts together.

When such leakage occurs it is even more serious in a mattress of this type than in one having the usual case or envelope made of ticking since a mattress of the latter type can be dried out, 15 whereas one like that disclosed in the present application is very difficult to dry. In order to prevent the entrance of water into the body of the mattress in the manner just described, I introduce a sealing medium between the tufts 3 and 20 the waterproof envelope which effectually closes the holes under the tufts. In the construction shown this sealing medium consists of a cement which will bond both to the tufts and also to the waterproof coating of the envelope. Referring to Fig. 3, the waterproof coating on the envelope 2 is indicated at a. Secured to the portion of this coating underlying the tuft 3 and adjacent to it, is a body 5 of cement which is adhesively united both to the coating and also to the tuft. The preferred practice is to use a cement of the same general nature as the coating a. For example, if this coating consists of a lacquer, such as one having a cellulose acetate base, the cement may be of exactly the same material. In fact, the cement may consist of the coating compound. After the mechanical operations on the mattress have been completed, a small quantity of this cement can be applied under each of the tufts and around the cord by means of a dropper or any suitable implement having a nozzle adapted to facilitate such application. When this operation has been completed on one side the mattress is allowed to rest long enough for the cement to harden, and subsequently the opposite side is treated in the same way. After the application of the cement, each tuft rests in a small puddle of cement which, upon hardening, secures the tuft firmly to the envelope and seals the crevice between the tuft and the envelope against the entrance of water.

If desired, the mattress may be provided with one or more screened ventilating openings, such as that shown at 6, Fig. 1, these openings being 55

placed in the side of the mattress where there is practically no danger of water entering them.

The invention is also applicable with advantage to mattresses of the common commercial types in which a fabric ticking, or other cover, previous to water, is used for the envelope. By cementing the tufts to the envelope in the manner above described, each tuft is permanently held snugly against the surface of the envelope even though the cord which secures the top and bottom tufts together may be broken. Often when a tuft, and particularly a button tuft, has been loosened by the compression of the mattress, it will become turned up edgewise and cause appreciable discomfort to the person sitting or lying on the mattress. Also, babies occasionally succeed in picking off a tuft and swallowing it. Ac-

cidents of this character are avoided by cementing the tufts in place, as above described.

While I have herein shown and described a preferred embodiment of my invention, it will be understood that minor changes may be made within the spirit and scope of the invention.

Having thus described my invention, what I desire to claim as new is:

A mattress including a waterproof top sheet, tufts located at suitable intervals on said sheet and secured in place by cords passing through holes in said top sheet, said tufts being secured to said top sheet by waterproof cement cooperating with the tufts to form a seal against the passage of water through said holes. 15

EDWARD ROSE.
